UNITED STATES PATENT OFFICE.

GEORGE MCKENZIE, OF EVERETT, WASHINGTON.

APPARATUS FOR LOCATING AND RAISING SUNKEN VESSELS.

1,176,229.

Specification of Letters Patent. Patented Mar. 21, 1916.

Application filed March 2, 1915. Serial No. 11,510.

To all whom it may concern:

Be it known that I, GEORGE MCKENZIE, citizen of the United States, residing at Everett, in the county of Snohomish and 5 State of Washington, have invented a certain new and useful Improvement in Apparatus for Locating and Raising Sunken Vessels, of which the following is a specification.

My invention relates to improvements in 10 means for indicating the location of sunken vessels and raising such sunken vessels to the surface of the water, and the particular object of my improvement is to provide inexpensive, simple and reliably operative devices for indicating the location of a submarine war vessel which has become uncontrollable and stranded on the sea bottom and for raising such vessel to the surface of the sea by the aid of a rescuing vessel; and 15 20 a further object of my improvement is to provide telephonic means of communication between such sunken submarine vessel and said rescuing vessel; and a still further object of my improvement is to provide 25 means by which air may be pumped from the surface of water into such sunken submarine vessel thus to furnish air to its crew until rescued.

I accomplish these objects by devices illustrated in the accompanying drawings, some 30 of which devices are similar in construction and operation to devices disclosed in United States Letters Patent Number 1,124,231, granted to me on date of January 5, 1915, 35 for "device for locating and raising sunken vessels" and in such accompanying drawings Figure 1 is a view in side elevation indicating a submarine vessel which embodies my invention as it may appear when helpless on the sea bottom; Fig. 2 is a view of 40 the same vessel in vertical cross-section on broken line x, x of Fig. 1, showing such vessel as it appears under normal conditions of operation; Fig. 3 is a view in vertical 45 mid-section of parts of my invention; Fig. 4 is a view in side elevation of other operative parts of my invention; Fig. 5 is a plan view of the structure shown in Fig. 4 with a portion of its cover removed better to 50 illustrate interior parts; Fig. 6 is a plan view of operative parts of my invention; and Fig. 7 is a view in vertical mid-section on broken line y, y , of Fig. 3.

Referring to the drawings, throughout 55 which like reference numerals indicate like parts, in Fig. 1, 8 indicates a submarine

war vessel as lying on the sea bottom in a disabled condition and on the surface of the sea are two buoys 9 and 10 to which are fixed signal flags 11 and 12 respectively. 60 Each of the buoys 9 and 10 is connected with the two members of a loop of a cable, as cables 13 and 14 respectively, which loop extends vertically downward into the hull of the vessel 8 wherein it is attached to 65 a winding-drum 15 in the manner indicated in Fig. 6, whereby said buoys 9 and 10 with their flags 11 and 12 respectively, displayed on the surface of the sea may serve as signals of distress as well as to indicate the location of the disabled vessel 8. When the vessel 8 is controllable under normal conditions of operation, either submerged or on the surface of the sea, then 70 the buoys 9 and 10 are each releasably secured to rest within a circular recess 16 75 formed in the deck of the vessel 8, in the manner shown in Figs. 2 and 3.

Extending downwardly from the bottom of each recess 16 to the top wall of an inclosing case 17 are two metal tubes 18 and 19, through each of which extends one of the members of the loop of cable, as the cable 14, the upper ends of such members being secured to eyebolts in the bottom wall 80 of the buoy 10 whereby if the buoy 10 be released to ascend upwardly through the water while the vessel 8 is submerged then the members of the cable loop 14 will be free to travel from the winding-drum 15 85 through the tubes 18 and 19 over idler-pulleys 20 and 21 which are rotatably mounted on suitably supported shafts, such idler-pulleys 20 and 21 and said winding-drum 15 being disposed within the inclosing case 90 17 which is secured to the keelson 22 of the vessel 8.

The joints between the tubes 18 and 19 and the bottom wall of the recess 16, and the joints between the top wall of the inclosing case 17, and the lower ends of said tubes 18 and 19 are water tight and also the inclosing case 17 is water tight whereby when the buoy 10 is released from the recess 16 and ascends upwardly, then no water can 100 gain access to the interior of the vessel 8 although water may gain admittance into the tubes 18 and 19 and the inclosing case 17.

If the vessel 8 becomes disabled, when 110 submerged, so that it cannot operate to rise to the surface of the water, then each of

the buoys 9 and 10 may be released from its recess 16 to ascend to the surface of the sea by devices shown in Figs. 3, 4 and 5, wherein two levers 23 and 24 are pivotally mounted on a bracket 25 secured to the bottom wall of the recess 16 in the deck of the vessel 8, the upper ends of which levers 23 and 24 are provided with hooks 26 and 27 respectively which are disposed opposite each other to adapt them to removably engage with barb-like notches disposed on opposite sides of a catch 28 which is formed like the head of an arrow and which is secured in the center of the under surface of the bottom wall of the buoy 10, while the lower end portions of said levers 23 and 24 are widely separated and are connected together by branches 29 of a chain 30, as shown more clearly in Fig. 3, whereby a downward pull of the chain 30 will cause the hooks 26 and 27 to separate and disengage from the notches in the catch 28 thus to release the buoy 10 which will then be free to ascend upwardly through the water to the surface thereof by reason of its buoyancy, carrying with it the ends of the members of the loop of cable 14.

Adjacent to and beneath the pivoted portion of the levers 23 and 24 is a helical spring 31 which is adapted to exert its force normally to make the hooks 26 and 27 approach each other to cause them to enter the notches of the catch 28, thus if there be no strain on the chain 30 when the buoy 10 is lowered into the recess 16 the arrow-like head of the catch 28 will spread apart the hooks 26 and 27 until they fall into the notches of the catch 28 there to be retained by the spring 31 until the chain 30 is drawn forcibly downward, the yielding soft rubber diaphragm 54 permitting such movement, thus to lock the buoy 10 in its position within the recess 16 in the obvious manner shown in Fig. 3.

45 The chain 30 extends downwardly between the tubes 18 and 19 and its lower end is connected to a lever 32 one end of which is pivotally attached to a bracket 33 secured to the top wall of the inclosing case 17 near one edge thereof, while the other end of such lever 32 is articulated to the upper end of a connecting rod 34 whose lower end is articulated with a crank-pin 35 which projects from the outerside of a ratchet-wheel 36, which ratchet-wheel 36 is rotatably mounted on a stud 37 secured to the side wall of the inclosing case 17, as shown in Fig. 5.

Secured on the top wall of the inclosing case 17 adjacent to the edge thereof are guide brackets 38 which serve to guide the lever 32 in its upward and downward swinging movements.

60 Swingly mounted on the stud 37 is a hand lever 39 to which is pivotally secured a pawl 40 which is disposed to adapt it to

releasably engage with the teeth of the ratchet-wheel 36, while another pawl 41 is pivotally attached to the side wall of the inclosing case 17 in such position that it may also releasably engage with the teeth of the ratchet-wheel 36 normally to prevent the ratchet-wheel 36 from turning in a clockwise direction. Thus if it be desired to release the buoy 10 to permit it to ascend to the surface of the water one may actuate 75 the lever 39 to rotate the ratchet-wheel 36 in a contra-clockwise direction whereby the connecting rod 34 will pull down the free end of the lever 32 which will cause the chain 30 to be drawn downwardly, which 80 chain 30 acting through its branches 29 will cause the lower ends of the levers 23 and 24 to approach each other against the force of the spring 31 thus to separate and disengage the hooks 26 and 27 from the catch 28 and 85 thereupon the buoy 10 will be free to rise.

In order that the officers of a rescuing ship may communicate by telephone with the officers of the submerged and disabled vessel 8, I have provided an electric conductor 42 which normally is wound upon a reel 43 disposed within the inclosing case 17, which conductor 42 is extended from such reel 43 into the lower end of the tube 19, thence up through such tube 19 into and 90 through an iron pipe 44 which is disposed to extend from the underside of the buoy 10 to the topmost portion thereof where it may be adapted, in a well known manner, to be connected to telephonic apparatus which 95 may be supplied by the rescuing party of a ship; while the inner end portion of the conductor 42 which is wound on the reel 43 may be disposed to adapt it to connect with telephone apparatus carried by the submarine vessel 8. When the vessel 8 is disabled and is resting on the bottom of the sea with the buoys 10 and 11 floating on the surface of the sea a rescuing party that is 100 provided with a suitable salvage vessel may raise the vessel 8 to the surface of the sea by hooking the two portions of each of the cables 13 and 14 and cutting them free from their buoys and drawing such end portions on board the salvage vessel until both of the cables 13 and 14 are wholly unwound from their respective drums 15 so that the loop end of each is disposed to encircle the idler pulley 20 whereupon one end of each of two 105 larger and stronger cables (for raising the vessel 8) may be attached to one member of the loop of a different one of the cables 13 and 14 and then each of said cables 13 and 14 may be hauled by a winch to draw such 110 larger cable down into the vessel 8 around the idler pulley 20 and up again on to the deck of the salvage ship, thus to replace each of the cables 13 and 14 with a larger and stronger cable both of whose ends may then 115 be hauled by a winch to raise the vessel 8 120 125 130.

by a strain on the pulley 20 which is securely associated with the keelson 22.

In Fig. 7 I have illustrated means for conducting fresh air from a point above a 5 buoy as the buoy 45, (which corresponds to the buoys 9 and 10) to the interior of a vessel whose deck is indicated by the numeral 46, which means comprises a hose 47 which, in the form of a coil, is disposed in 10 a receptacle 48 whose open top portion is fastened to the under surface of the bottom wall of the recess 49, through which bottom wall is an opening 50 which registers with the open top of the receptacle 48, and 15 the upper end of such hose is connected to a pipe 51 which is secured to the buoy 45 to extend upwardly therethrough to project its top end above the top wall of the buoy 45 and such top end of the pipe 51 20 is provided with a removable cap 52, while the lower end of the coil of hose 47 connects with a nipple 53 which is disposed to extend through the bottom wall of the receptacle 48. Thus if the vessel be resting 25 on the bottom of the sea in a disabled condition then the buoy 45 may be released, by means hereinbefore described, whereby the buoy 45 may ascend to the surface of the water carrying with it the upper end of 30 the hose 47 and uncoiling such hose 47 as the buoy 45 rises, whereby, while the buoy 45 floats on the surface of the sea, the crew of a rescue ship may remove the cap 52 and attach another hose leading to an air 35 compressor on board of such rescue ship which compressor may then be operated to force fresh air through said hose 47 into the submerged vessel. Obviously, in a similar manner another hose may be associated 40 with the submarine vessel and with the buoy 45 through which foul air may escape from such vessel. Of course, an air pump may be disposed within the submerged vessel for pumping air inwardly through the hose 47 45 after the cap 52 has been removed by one of the rescuing party.

Manifestly, changes may be made in the form, dimensions and arrangement of parts of my invention without departing from the 50 spirit thereof.

What I claim is:

1. The combination with the hull of a submarine war vessel, of a hollow, air-tight

buoy made of sheet metal and formed to adapt it normally to rest on a seat provided 55 on the deck of said vessel, a notched catch of arrow-head-like form secured to the central portion of the bottom of said buoy to project downwardly therefrom, a pair of levers pivotally secured to the underside of 60 the deck of said vessel, said levers each having its upper end portion provided with a hook-like member and disposed so that such end portion projects upwardly through said deck to releasably engage said hook-like members with said notched catch to lock said buoy in its seat on said deck, a resilient packing surrounding said levers and constituting means for preventing the entry of water through the deck and also 65 spring means for normally holding the levers in engaging position, pawl and ratchet mechanism mounted in said vessel, and a cable connecting said pawl and ratchet mechanism with said levers whereby the 70 levers are released from said notched catch to permit the buoy to rise.

2. A vessel including a hull, a watertight casing within the hull, tubes connecting said casing with an opening in the upper deck of the vessel, a buoyant member seated in said opening, a reel within said casing, a cable connected at one end to said reel and at its other end to said member, coöperating means carried by said member 85 and casing adapted to hold the buoyant member on its seat, said coöperating means including a pair of clutch levers, the deck being provided with an opening through which said clutch levers pass, a resilient 90 diaphragm mounted in the opening and closely engaging the clutch levers to prevent access of water and to constitute spring means for holding the clutch levers in engaging position, and pawl and ratchet 95 mechanism associated with said means adapted to release the said member to permit the same to rise.

In witness whereof I hereunto subscribe my name this eighteenth day of February, 100 A. D. 1915.

GEORGE MCKENZIE.
